UNITED STATES PATENT OFFICE.

ERIK PALM, OF ELDRED, MINNESOTA.

MANURE-SPREADER.

947,453.

Specification of Letters Patent. Patented Jan. 25, 1910.

Application filed July 20, 1909. Serial No. 508,570.

To all whom it may concern:

Be it known that I, ERIK PALM, citizen of the United States, residing at Eldred, in the county of Polk and State of Minnesota, have invented new and useful Improvements in Manure-Spreaders, of which the following is a specification.

My present invention has to do with manure spreaders, and one of its objects is the provision of a simple, practical and efficient manure spreader, the manure-discharging means of which may be conveniently put into and out of operation by the driver of the spreader.

Another object is the provision of a manure-spreading apparatus, of high efficiency, constructed with a view of being readily arranged and secured in proper position, relative to the running gear and the box of an ordinary farm wagon, and used to advantage in combination therewith.

Another object is the provision in a manure spreader, of an improved endless apron for moving manure rearwardly in the box.

Another object is the provision of improved means for transmitting motion to the said endless apron.

With the foregoing in view, the invention will be fully understood from the following description and claims when the same are read in connection with the drawings, accompanying and forming part of this specification, in which:

Figure 1 is a perspective view showing my improvements on the running gear of an ordinary farm wagon. Fig. 2 is an enlarged, broken side elevation with all of the running gear omitted except a portion of one rear wheel. Fig. 2² is a detail section illustrative of the manner in which the pinions D' are clutched upon the trunnions B' of the toothed cylinder C'. Fig. 3 is a detail broken plan view. Fig. 4 is a broken, longitudinal vertical section showing the arrangement of the endless apron relative to the cylinder and to the bottom of the box and the base frame of the latter. Fig. 5 is a broken side elevation showing the box, its base frame, one of the front supports, one of the rear supports, one of the fenders, and a portion of one of the metallic braces of my improvements, together with the rear bolster and axle of a wagon running gear. Fig. 6 is a perspective view showing one of the metallic braces *per se*.

Similar letters of reference designate cor-

responding parts in all of the views of the drawings.

The running gear of the wagon employed in connection with my improved apparatus, including the rear bolster and the front bolster, is preferably of the well-known, conventional construction; and in pursuance of my invention large sprocket gears A are fixed on the rear ground wheels B of the running gear, it being contemplated to supply the said gears A and sprocket belts C with the remainder of the manure-spreading apparatus, and to clip, at a a, or otherwise connect the sprocket gears A to the spokes of the wheels B in such manner that skilled labor is not required. I also contemplate supplying the wagon box D with the remainder of the apparatus; the said box being open at its rear end, and having a front end wall or board b designed to be maintained in a position slightly raised from the bottom of the box, as shown, when the spreading apparatus is to be operated. I would also have it understood that I prefer to equip the box D with a driver's seat E, having end uprights c, designed to rest on the side walls of the box D, and straps d fixed to said uprights and adapted to lap the side walls of the box, and also having arms e, of metal fixed to and extending downwardly and then forwardly from the outer sides of the said uprights c. The said arms e are pivoted on a horizontal rod f extending across the body D, in front of the wall b, and hence when the box D is to be loaded with manure, the seat E may be swung forwardly and downwardly to a position in front of the wall b, and then, after the loading is completed, the seat may be swung back to the position shown where its uprights c rest on and are supported by the side walls of box D.

My invention further contemplates providing the box D with a base frame, arranged under the box and fixedly connected thereto by straps F or other suitable means. The said frame comprises spaced rear portions g extending laterally outward beyond the vertical plane of each side wall of the box, a front portion h extending laterally outward beyond the vertical plane of each side wall of the box, longitudinal, spaced bars i arranged under said portions g and h, and cross-bars j arranged below the bars i and separated by an intervening space as shown. Each of the longitudinal bars i is provided on its under side with a brace G,

preferably of metal, designed to bear against the rear side of the rear axle and bolster of the wagon running gear, as shown in Fig. 6 with a view of more strongly holding the box D and its base frame against forward movement, relative to the running gear of the wagon when the manure spreading mechanism is in operation.

It will be readily understood from the foregoing that the box D and its base frame may be placed on and removed from the running gear of an ordinary farm wagon with great facility and without entailing change in the construction of the running gear or the employment of skilled labor. It will also be understood that when the box D and its base frame are placed on the running gear of a farm wagon, adequate space will be afforded between the longitudinal bars *i* for the travel of the lower stretch of the endless apron comprised in the manure-spreading mechanism hereinafter described.

I have laid particular stress upon the extension of the base-frame portions *g* and *h* laterally outward beyond the side walls of the box D, because said base-frame portions constitute important features of my invention. This will be fully appreciated when it is stated that the rear portion of the manure-spreading mechanism is carried by two metallic supports H, resting on the frame portions *g*, at opposite sides of the body D, and each connected by two or three bolts *k* to portions *g*, and the front portion of said manure-spreading mechanism is carried by two metallic supports I, resting on the frame portions *h* and each connected by a single bolt *l* to the adjacent portion *h*, and when it is also stated that the endless apron J of the manure-spreading mechanism is adapted to be opened to permit of its removal from the box D. Thus when the apron J is opened by disconnecting meeting ends thereof, the apron may be separated from the box D, and then by simply removing the four or six short bolts *k* and the two short bolts *l*, the supports H and I and the mechanism or manure-spreading parts carried thereby are disconnected from the box D and the base-frame thereof, and may be lifted off, leaving the said box and base-frame free to be used after the manner of an ordinary wagon box and the base-frame thereof, at which time the base-frame will serve merely to support the box and to hold the same against endwise movement on the bolsters of the running gear.

The endless apron J comprises transverse followers *m*, preferably of angular form in cross-section, and sprocket belts *n* to which the followers are connected and between which said followers extend.

Journaled in and carried by the forward metallic supports I is a transverse shaft K, and secured to said shaft are cranks L, Figs.

1 and 2. One of the said cranks—namely, the one at the right-hand side of the apparatus, is preferably formed integral with a hand lever M, and connected to and extending rearwardly from both cranks L are endwise movable rods N, the office of which will be hereinafter set forth. It is well, however, to here state that when the points at which the cranks L are connected to the rods N are moved downwardly to positions 75 in front of and in the same horizontal plane as the longitudinal center of the shaft K, the parts will rest in a dead center, and consequently the rods N cannot move rearwardly until the cranks L are swung, 80 through the medium of the lever M and the shaft K, upwardly from said position.

Loosely connected to and pendent from the transverse shaft K are hangers P, each of which is provided with a lateral lug *p*, 85 and journaled in the said hangers P is a transverse shaft Q, bearing sprocket wheels R around which pass the belts *n* of the endless apron J. The lugs *p* on hangers P are for the engagement of longitudinally disposed screws S, bearing in lugs *r* on the metallic supports I, and hence it will be manifest that the apron J may be conveniently kept taut; also, that when the screws S are moved rearwardly to allow the hangers 95 P to swing in the same direction, the apron J is slackened, and its meeting ends may then be disconnected, for the purpose before stated.

As best shown in Figs. 2, 3 and 5, each of the metallic supports H is provided with a stub shaft *s*, an approximately horizontal guideway *t*, open at its rear end, and a journal bearing *u*, the latter disposed about the distance shown below the shaft *s*. It will 100 also be observed that bolted or otherwise fixed to each metallic support H is a bracket T which extends upwardly from the support. Fixedly connected to the brackets T are fenders U, preferably of wood, which rest 110 at the outer sides of the side walls of the box D and extend rearwardly therefrom, and have straps *v* on their inner sides, Fig. 1 designed to lap the side walls of the box D and hold the fenders there-against. The said brackets T also serve to support the rake U' 115 which preferably comprises a cross-bar *w*, and teeth *x* extending downwardly and rearwardly therefrom.

Loosely mounted on the stub shafts *s* of the metallic supports H are sprocket gears V and spur gears W; the said sprocket gears V being each fixed to the adjacent spur gear W, and being each designed to be connected through one of the sprocket belts C with the adjacent sprocket gear A, so that each sprocket gear V is rotated from the ground wheel B at that side of the spreader. For the purpose of maintaining the belts C in a taut state, idler pulleys X adjustably con- 120 125 130

nected with the base-frame of the box D are provided.

Journaled in the bearings *u* of the metallic supports H is a transverse shaft Y, upon which are sprocket gears *y* around which pass the belts *n* of the apron J. At one end the shaft Y has fixed thereon a ratchet Z, Fig. 2, for a purpose hereinafter set forth.

Slidable fore and aft in the guideways *t* of the metallic supports H are bearing boxes A', and journaled in the said boxes and movable fore and aft therewith are the trunnions B' of the toothed cylinder C', which latter is disposed between the fenders U. D' D' are pinions clutched on the trunnions B', and designed when the boxes A' are retained in their foremost positions, to intermesh with the spur gears W, so as to assure rotation of the cylinder C' in the direction indicated by arrow. The boxes A' are retained in their foremost position by the means before described and comprising the rods N, and this against the action of springs E' arranged in front of the boxes A' and interposed between said boxes and suitable parts of the supports H. The said springs E' serve, when the cranks L are moved out of the dead center before referred to, to press the boxes A' rearwardly, whereupon the pinions D' will be moved out of engagement with the spur gears W, and the cylinder C' will be rendered idle. When, however, the hand lever M is manipulated to draw the boxes A' forwardly, the pinions D' will be put into mesh with the spur gears W and will be retained in such position in the manner before described for the rotation of the cylinder C' from the ground wheels B. The pinions D' are loose upon the trunnions B', and said pinions D' are clutched on the trunnions B', as before stated, through the medium of disks F' fixed on the trunnions; the clutching of the pinions to the disks being such that the trunnions B' will rotate when the pinions are rotated, and yet one of the trunnions is adapted to rotate while the pinion thereon is at rest or is rotating slower than the trunnions and the cylinder C'. Thus when the apparatus is being turned, the parts are not subjected to strain because of the fact that the inner of the wheels B does not rotate as fast as the outer of said wheels.

The pinions D' may be clutched on the trunnions B' as stated, in any manner consonant with the purpose thereof. For instance each disk F' may be provided with an interior annulus having ratchet teeth *a* disposed as shown in Fig. 2^a and each pinion D' may be provided with a spring-backed pawl *b* adapted to engage one of the teeth *a* and thereby rotate the disk F' in the direction of the arrow thereon. When, however, the pinion is at rest or is rotating

slower than the trunnion B' and the disk F' thereon, the said disk is enabled to rotate in the direction indicated independently of the pinion and the pawl thereon.

For the purpose of transmitting a step by step motion from one of the disks F' to the transverse shaft Y, I provide the said disk with a crank pin G'; Fig. 2, and I also provide the mechanism best shown in Fig. 2. The said mechanism comprises a detent H', backed by a spring I' and adapted to prevent retrograde movement of the ratchet Z, a vertically swinging lever J' loosely mounted on the shaft Y or otherwise pivotally connected with the adjacent support H and having a slot *a'*, spring-backed pawls *b'* and *c'*, pivoted to the lever J' and positioned to engage the ratchet; the pawl *b'* being smaller than the pawl *c'* in about the proportion shown, and a pitman K' interposed between the crank pin G' and the lever J' and connected to the latter by a bolt adjustably fixed in the slot A' so that the movements of the lever J' by the pitman may be regulated as occasion demands. The teeth of the ratchet Z are preferably made large for the sake of strength and durability, and the pawls *b'* and *c'* are preferably arranged so that they alternate in engaging the ratchet—i. e., first one and then the other of the pawls engage teeth of the ratchet to rotate the latter. Because of this arrangement it will be understood that notwithstanding the large size of the ratchet teeth there will be little or no lost motion incidental to downward movements of the lever J' inasmuch as one or the other of the pawls is always in position to transmit motion from the lever J' to the ratchet Z.

It will be manifest from the foregoing that synchronously with the rotation of the toothed cylinder C', the shaft Y will be turned step by step to move the upper stretch of the apron J rearwardly above the bottom of the box D and enable the novel followers *m* of the apron to move the manure in said box to the cylinder C'; by which the manure will be scattered broadcast. It will also be manifest that by adjusting the pitman K' relative to the lever J' the length of each rearward movement of the upper stretch of the apron J may be increased or diminished in the discretion of the party operating the machine.

In the practical operation of my invention, the box D is loaded with manure, and the spreader is driven to the point at which the spreading of the manure is to be started; the cylinder C' being then in its rear and idle position. When the said point is reached, the driver without stopping his team manipulates the lever M to put the cylinder C' and the means for moving the manure rearwardly in operation, whereupon

the manure will be efficiently spread broadcast until the lever M is released or until the load of manure in the box D is exhausted.

The construction herein illustrated and described constitutes the best practical embodiment of my invention that I have as yet devised, but it is obvious that in the future practice of the invention such changes or modifications may be made as do not involve departure from the scope of my invention as defined in the claims appended.

Having described my invention, what I claim and desire to secure by Letters-Patent, is:

15 1. In a manure spreader, the combination of a box open at its rear end and having a front end wall adapted to be maintained in a raised position, a base frame fixedly connected with the box and having portions extending laterally outward beyond the side walls of the box, adjacent the rear and forward ends thereof, and also having longitudinal spaced bars arranged under the said portions, rear supports arranged at the outer 20 sides of the side walls of the box and disposed on and detachably connected to the rear laterally-extended portions of the base frame, front supports arranged at the outer sides of the side walls of the box and disposed on and detachably connected to the forward laterally-extended portions of the base frame, a toothed cylinder carried by the rear supports, a transverse shaft carried by the rear supports and disposed in rear of the box, a transverse shaft carried by the front supports and disposed in front of the box, an endless apron, adapted to be opened, mounted on said shafts and having one of its stretches disposed above the bottom of 25 the box and its other stretch disposed below said bottom and between the longitudinal bars of the base frame, and a drive connection carried by one of the rear supports and adapted to transmit motion from the toothed cylinder to the rear apron shaft.

2. In a manure spreader, the combination of a box open at its rear end and having a front end wall adapted to be maintained in a raised position, a base frame fixedly connected with the box and having portions extending laterally outward beyond the side walls of the box, adjacent the rear and forward ends thereof, and also having longitudinal spaced bars arranged under the said portions, rear supports arranged at the outer sides of the side walls of the box and disposed on and detachably connected to the rear laterally-extended portions of the base frame, front supports arranged at the outer sides of the side walls of the box and disposed on and detachably connected to the forward laterally-extended portions of the base frame, a toothed cylinder carried by the rear supports, a transverse shaft carried by the rear supports and disposed in rear of the

box, a transverse shaft carried by the front supports and disposed in front of the box, an endless apron, adapted to be opened, mounted on said shafts and having one of its stretches disposed above the bottom of 70 the box and its other stretch disposed below said bottom and between the longitudinal bars of the base frame, a drive connection carried by one of the rear supports and adapted to transmit motion from the toothed cylinder to the rear apron shaft, brackets fixed to the rear supports, fenders carried by said brackets and having straps for detachably holding them to the side walls of the box, and a rake disposed above the 80 toothed cylinder and carried by the said brackets.

3. In a manure spreader, the combination of a box open at its rear end and having a front end wall adapted to be maintained in a raised position, a base frame fixedly connected with the box and having portions extending laterally outward beyond the side walls of the box, adjacent the rear and forward ends thereof, and also having longitudinal spaced bars arranged under the said portions, rear supports arranged at the outer sides of the side walls of the box and disposed on and detachably connected to the rear laterally-extended portions of the base frame, front supports arranged at the outer sides of the side walls of the box and disposed on and detachably connected to the forward laterally-extended portions of the base frame, a toothed cylinder carried by the rear supports, a transverse shaft carried by the rear supports and disposed in rear of the box, a forward transverse shaft disposed in front of the box, bearings therefor carried by and movable fore and aft on the forward supports, means carried by the forward supports for adjusting said bearings forwardly and adjustably holding the same against rearward movement, an endless apron, adapted to be opened, mounted on 100 the transverse shafts and having one of its stretches disposed above the bottom of the box and its other stretch disposed below said bottom and between the longitudinal bars of the base frame, and a drive connection carried by one of the rear supports and adapted to transmit motion from the toothed cylinder to the rear apron shaft.

4. In a manure spreader, the combination of a box open at its rear end and having a forward end wall adapted to be maintained in a raised position, a base frame fixedly connected with the box and having portions extending laterally outward beyond the side walls of the box near the ends thereof and also having spaced portions adapted to bear on a running gear and between which is a longitudinal passage for the lower stretch of an endless apron, rear supports carried by the rear laterally-extended portions of 110 115 120 125 130

the base frame and arranged outside the box, front supports carried by the forward laterally extending portions of the base frame and also arranged outside the box, a toothed 5 cylinder carried by the rear supports, a transverse shaft carried by the rear supports and disposed in rear of the box, a transverse shaft carried by the front supports and disposed in front of the box, the 10 said endless apron mounted on said shafts and having one of its stretches disposed above the bottom of the box and its other stretch disposed below said bottom and in the aforesaid passage, and a drive connection 15 carried by one of the rear supports and adapted to transmit motion from the toothed cylinder to the rear apron shaft.

5. The combination in a manure spreader, of supporting means, spur gears mounted on 20 said supporting means, means for rotating said spur gears, spring-pressed bearing means located in rear of the spur gears and yieldingly held against movement toward the same, a toothed cylinder journaled in 25 said bearing means and having pinions adapted, in the forward position of the bearing means, to engage the said spur gears, and means for moving the bearing means forward and holding the same against rear- 30 ward movement.

6. The combination in a manure spreader, of supporting means having side portions and longitudinal guideways therein, spur 35 gears mounted on said side portions of the supporting means, means for rotating said spur gears, bearings movable fore and aft in said guideways, a toothed cylinder journaled in said bearings and having pinions adapted to engage the said spur gears, springs inter- 40 posed between the forward sides of the bearings and said side portions of the supporting means and adapted to press the bearings rearwardly, and means for moving the bearings forwardly and holding the same against 45 rearward movement.

7. The combination in a manure spreader, of supporting means having side portions and longitudinal guideways therein, spur 50 gears mounted on said side portions of the supporting means, means for rotating said spur gears, bearings movable fore and aft in said guideways, a toothed cylinder jour-

naled in said bearings and having pinions adapted to engage the said spur gears, springs interposed between the forward 55 sides of the bearings and said side portions of the supporting means and adapted to press the bearings rearwardly, a transverse shaft journaled in the forward portion of the supporting means and having a lever 60 and also having cranks, longitudinal rods connected at their rear ends with the said bearings and having their forward ends connected to said cranks and adapted, when the bearings are in their foremost position, to 65 rest in front of and in line with the center of movement of the cranks.

8. The combination in a manure spreader, of supporting means having side portions and longitudinal guideways therein, spur 70 gears mounted on said side portions of the supporting means, means for rotating said spur gears, bearings movable fore and aft in said guideways, a toothed cylinder journaled in said bearings, pinions clutched to the journals of the toothed cylinder and adapted to engage the said spur gears, springs interposed between the forward sides of the bearings and said side portions of the supporting means and adapted to press the bearings 75 rearwardly, and means for moving the bearings forwardly and holding the same against 80 rearward movement.

9. The combination in a manure spreader, of supporting means, a shaft journaled 85 therein and adapted to transmit motion to an endless apron, a spur gear mounted on said supporting means, means for rotating said spur gear, fore and aft movable bearing means carried by said supporting means 90 and adapted when released to move rearwardly relative to said spur gear, a toothed cylinder journaled in said bearing means and having a pinion, and means movable fore and aft with the said bearing means and 95 adapted to transmit motion from the toothed cylinder to the transverse shaft.

In testimony whereof I have hereunto set my hand in presence of two subscribing witnesses.

ERIK PALM.
